UNITED STATES PATENT OFFICE.

EMMETT H. HERNDON, OF SANFORD, FLORIDA.

MOTOR.

No. 896,448.

Specification of Letters Patent. Patented Aug. 18, 1908.

Application filed July 10, 1907. Serial No. 383,056.

To all whom it may concern:

Be it known that I, EMMETT H. HERNDON, a citizen of the United States, residing at Sanford, in the county of Orange and State 5 of Florida, have invented a new and useful Motor, of which the following is a specification.

This invention has reference to improvement in motors or engines designed to be operated by fluids under pressure, such for instance as the gases generated by the ignition of an explosive compound.

The invention comprises an engine in which there is provided a shaft carrying a rotative 15 member with a helical return groove, and parallel with the axis of the rotative member is a cylinder or cylinders, each containing a reciprocating piston with a projection at an intermediate point thereon and entering the 20 groove after passing through a slot in a guiding member. The projection carries anti-friction rollers one against the walls of the groove and the other incased in the walls of the slot. Furthermore there are hollow ex- 25 haust heads having bearings to serve for the engine shaft and the engine cylinders have their exhaust ports opening into the heads.

The invention also consists in certain novel 30 features of construction and arrangement of parts, hereinafter fully described, illustrated in the accompanying drawings, and particu- 35 larly pointed out in the appended claims, it being understood that various changes in the form, proportions, size and minor details of the structure may be made without depart- 40 ing from the spirit or sacrificing any of the advantages of the invention.

In the accompanying drawings:—Figure 1 is a side elevation of a motor constructed in accordance with the invention, one of the cylinders being shown in section and parts being broken away and some parts omitted. Fig. 2 is a transverse sectional view of the motor on the line 2—2 of Fig. 1. Fig. 3 is a de- 45 tail sectional view of one of the shaft bearings. Fig. 4 is a transverse sectional view of the shaft showing the spark timer. Fig. 5 is a detail view, partly in section showing a preferred form of shaft and piston connec- 50 tion. Fig. 6 is a sectional elevation, partly in the nature of a diagram, showing the arrangement of the cooling devices. Fig. 7 is a diagram showing the operation of the main and auxiliary pistons.

Similar numerals of reference are employed 55 to indicate corresponding parts throughout the several figures of the drawings.

The general frame of the machine includes a pair of approximately triangular boxes 10, which are rigidly secured together by a cylindrical shell 11. At the center of each of the boxes is a bearing for the support of the shaft 15, and each box is provided with semi-circular depressions 16 for the reception of the cylinders 17, three pairs being shown in the 60 present instance, the cylinders being confined in place by straps 18 and other securing devices, if necessary.

The boxes 10 are hollow and constitute ex- 65 haust heads which are in free communication with the cylinders through ports 20, the latter being arranged to open when the piston reaches the limit of the working stroke, and both boxes communicate with a muffler 21 having a discharge pipe 22 through which the 70 products of combustion from all of the cylinders finally escape.

In order to prevent undue heating of the 75 shaft bearings, the central portion of each of the boxes is arranged to receive a hollow ring 80 23 through which air is circulated in the manner hereinafter described, and the inner wall of each ring is provided with threads for the reception of ball races 24, these serving in connection with ball races 25 on the shaft for 85 the reception of anti-friction balls 26.

Secured rigidly to the shaft at a point be- 90 tween the two boxes is a drum 27 that is pro- 95 vided with a return helical groove 28 of such pitch that there will not be undue friction be- 100 tween the walls of the groove and the piston actuated members which enter such groove.

The cylinders are arranged in pairs, those 105 constituting each pair being arranged with their axes in alinement and within each pair 110 of cylinders fits double ended pistons 29. Projecting from the central portion of each piston is a stud 30 carrying two anti-friction 115 rollers 31 and 32, all of the rollers 32 entering the helical groove of the drum 27, while all of 120 the rollers 31 are arranged for contact with the walls of the slots 33 that are formed in the cylindrical shell 11. These slots 33 ex- 125 tend longitudinally of the shell and are par- 130 allel with the axes of the shaft and cylinders, so that they serve to maintain the studs 30 135 in proper position and prevent any turning of the pistons on their axes, so that the pistons

proper are not subjected to any torsional strain from the engagement of the rollers 32 with the walls of the helical slot 28.

Each of the pistons 29 is preferably in the form of a hollow cylinder closed at both ends and preferably of uniform diameter throughout its entire length, although it may be in the form of a pair of piston heads connected by a stem of less diameter than the heads.

10 Each of the cylinders is of precisely the same construction, the explosion chamber having a cap or cover 38 from which extends a tube 39, the axis of which is coincident with that of the cylinder. Through this 15 tube passes a rod 40 carrying at its inner end an auxiliary piston 41 in which are formed one or more transverse ports 42. These ports are provided with valves 43 that are normally held in closed position by springs 44 20 coiled around the valve stems and bearing at one end against the piston and at the opposite end against adjustable nuts carried by the stem. The outer end of the rod 40 carries a hook 45 to which the outer end of a 25 tension spring 46 may be attached, the inner end of the spring being connected to an eye on the head of the explosion chamber, the hook projecting through an elongated slot 47 formed in the wall of the tube 39, and said 30 spring tending at all times to force the auxiliary piston 41 away from the head of the explosion chamber.

Projecting from the stem 40 is an anti-friction roller 48 that is mounted on a stem 49 passing through a slot 50 formed in tube 39. This roller is arranged to be engaged by a cam 51 on the shaft, the shaft being provided with two cams one for each set of operating cylinders at each end of the motor.

40 At the explosion chamber head is an inlet 53 leading from the carburetor or other source of supply and through which the explosive compound is admitted to the cylinder. Arranged slightly in advance of each 45 auxiliary piston is a spark 54 of any ordinary construction, provision being made for controlling the igniting circuits in order to advance or retard the spark, as desired.

50 In the operation of the motor as a two cycle engine reference is had to the cylinder shown in Fig. 1, wherein the piston 29 is traveling toward the right and has nearly reached the end of the working stroke, it being observed that the escape port 20 of the 55 left hand cylinder is nearly full open. During this working stroke the pressure of gases within the cylinder has kept the auxiliary piston stationary, although the roller 48 of the latter is at this time out of engagement 60 with its operating cam 51. As soon, however, as the port 20 opens to such an extent as to permit the partial discharge of the explosive compound the pressure in the cylinder will reduce to a point below the stress 65 exerted by the spring 46, which at this time

has been placed under tension. When the pressure reduces to a point below the strength of the spring, the latter in retracting will force the auxiliary piston inward toward the exhaust port, thereby forcing out the remainder of the explosive charge, and, at the same time, creating a partial vacuum at the explosion chamber end of the cylinder, thereby causing an inflow of an explosive charge, and during this movement the valves 75 43 will remain closed in order to prevent the admixture of the fresh charge with the exploded gases.

As the anti-friction roller of the piston makes the turn in the helical groove 28, the 80 roller 48 of the auxiliary piston will be engaged by the cam 51 and the auxiliary piston will be moved outward by the cam in advance of the piston 29, as will be evident on reference to the diagram Fig. 7, where the inclination 85 of the cam is shown to be much quicker than the inclination of the groove, so that the auxiliary piston will arrive at the end of its out stroke or the stroke towards the explosion chamber head long before the main piston completes its stroke in the same direction. During this out stroke of the auxiliary piston the valves 43 open and the fresh charge passes to the space between the two pistons and is compressed therebetween as 90 the main piston completes its stroke, and at the end of this stroke the fresh charge of compressed explosive compound is ignited by the spark plug and another working stroke is effected.

100 Around the explosive chamber of each cylinder is arranged a plurality of air circulating passages 60, all of which are approximately semi-circular in cross section, although the shape is unimportant. These 105 passages are connected to headers 61 and 62 of which the headers 62 are connected to the air jackets 23 around the shaft bearings. Each jacket 23 is provided with a diaphragm 66 and is connected at one side of the diaphragm to a fluid supply pipe 67 through which air or other cooling fluid is directed, the air passing through the jackets and thence to the headers 62, after which the air flows through the passages 60 to the headers 110 61 for the purpose of reducing the temperature of the explosion chamber. The exhaust air from the headers passes through pipes 68 to a nozzle 69 that is arranged at the axis of the discharge port 22 of the muffler, so that the jet of discharging air may act after the manner of an inspirator for the purpose of 115 causing an outflow of the exhaust gases from the muffler and the exhaust boxes 10. This, of course, will create a slight vacuum within 120 the boxes 10 so that the exhaust may freely pass through the ports 20 from the cylinders.

125 The sparking apparatus is preferably in the form of a ring 70 mounted in an annular bearing 71 surrounding and concentric with 130

the shaft, there being two of such rings 70, one at each end of the motor, and each ring carrying a number of sets of terminals 72 corresponding to the number of cylinders. 5 These terminals are arranged to be engaged by a pin 73 projecting from the shaft, and as the latter rotates the terminals will be successively engaged for the purpose of first closing and then opening the circuits and 10 thus producing the sparks at the sparking plug. The ring 70 is mounted in a bearing 75 and is provided with a handle 76 by which it may be turned for the purpose of advancing or retarding the spark as may be required.

When the engine is to be operated on the four cycle principle the spring 46 is detached from the hook 45 and the rod 40 is locked to the tube 39 so as to prevent movement of the 20 auxiliary piston 42, the rod 40 being provided with an opening 79 into which a suitable pin may be inserted for this purpose. The device will then operate as an ordinary four cycle engine with the exception that the 25 exhaust port will be under the control of the main piston and will be opened by the piston when the latter reaches the limit of the working stroke. Owing to the partial vacuum created in the exhaust passages as 30 hereinbefore described, the major portion or all of the exploded charge will be withdrawn from the cylinder at the end of the working stroke, so that the piston is free to return to the explosion chamber end of the 35 cylinder in readiness for the following suction stroke.

In the construction of large engines, it is preferred to employ double grooves 28' and for this purpose the drum proper is provided 40 with a helical return rib 80, and on said drum are mounted two sleeves 81, the ends of which follow the contour of the rib and are spaced therefrom to form the two grooves 28'. These sleeves may be adjusted 45 toward and from the central rib by means of tapered keys 83 that extend through slots formed in the sleeves and drum, the keys being preferably provided with laterally projecting arms 84 through which pass bolts or 50 screws 85 that fit within threaded openings near the end portions of the drum. This provides for taking up any wear which may occur in the walls of the grooves. The single groove drum is also provided with adjusting means, one or both of the sleeves which form the walls of the slot being adjustable to compensate for wear.

In Fig. 1 keys 83 are shown for both members of the drum 27. In the structure of 60 Fig. 1 the keys and controlling means therefor may be the same as those shown in Fig. 5.

In order to prevent danger of explosion in the muffler, the latter is preferably provided

with a safety valve 88 which may be opened 65 in case of excess pressure.

It will be observed that the construction is such that the engine will run with precisely the same power in either direction and that any suitable fluids under pressure with 70 which the engine is adapted to operate, may be used.

I claim:—

1. In a motor, a rotative member having a helical return groove, the walls of said groove 75 being adjustable to compensate for wear, a pair of axially aligned cylinders, a double ended piston mounted in said cylinders, a stationary guide having a slot, the walls of 80 which are parallel with the axes of the cylinders and the rotative member, a stud projecting from the piston, and a pair of anti-friction rollers carried by the stud, one of such rollers engaging the walls of the groove, and the other the walls of the slot. 85

2. In a motor, a shaft, a member thereon having a helical return groove, a pair of hollow exhaust heads having supporting bearings for the shaft, a pair of axially aligned cylinders carried by said heads and provided 90 with exhaust ports in communication with the heads, a double ended piston mounted in the cylinders, and a projection extending from the piston and entering the groove.

3. In a motor, a pair of spaced hollow exhaust heads, bearings carried by said heads, a shaft mounted in said bearings, a member on the shaft provided with a helical return groove, a pair of axially aligned cylinders rigidly secured to said heads and having exhaust 95 ports in communication with the heads, a piston mounted in the cylinders, a fixed guide extending between and connecting the heads, said guide having a longitudinal slot, the walls of which are parallel with 100 the axes of the cylinders, a stud projecting from the piston, and a pair of anti-friction rollers carried by the stud, one of the rollers engaging the walls of the groove and the other the walls of the slot. 110

4. In a motor, a pair of spaced hollow exhaust heads, bearings carried thereby, a shaft mounted in said bearings, a member on the shaft provided with a helical return groove, a cylindrical shell surrounding the 115 shaft and connecting the heads, said shell being provided with a plurality of longitudinally disposed slots, a plurality of pairs of cylinders rigidly secured to the heads and forming connections between them, said 120 cylinders having exhaust ports that communicate with the heads, a double ended piston mounted in each pair of cylinders, a stud projecting from each piston, a pair of anti-friction rollers on each stud, one anti-friction 125 roller entering the groove and the other engaging the walls of one of the slots.

5. In a motor, a pair of hollow exhaust

heads, each having a separate opening, an annular cooling jacket mounted in said opening, ball races supported by the jacket, a shaft also having ball races, anti-friction balls mounted in the ball races, a member on the shaft provided with a helical return groove, a pair of axially alined cylinders supported by the heads and provided with exhaust ports in communication therewith, 10 cooling jackets surrounding the cylinders, air circulating connections between the cooling jackets around the bearings and those around the cylinders, a piston mounted in the cylinders, and a projection extending 15 from the piston and entering the groove.

6. In a motor, a pair of spaced hollow exhaust heads, each having a central opening, a cooling jacket mounted in said opening, ball races supported by the jacket, a shaft 20 also having ball races, a member on the shaft provided with a helical return groove, anti-friction balls mounted in the races, a pair of axially alined cylinders rigidly supported by the exhaust heads and having exhaust ports 25 in communication with said heads, a double ended piston mounted in said cylinders, a projection extending from the piston and entering said groove, an air jacket surrounding each cylinder and comprising a pair of head- 30 ers and intermediate connecting passages,

and air circulating connections between the cooling jacket around the bearings and the headers.

7. In an engine of the class described, a shaft, a drum thereon, a pair of spaced sleeves on the drum each arranged to form one edge or wall of a helical groove, means for adjusting said sleeves to take up wear, a cylinder, a reciprocating piston therein, and means extending from the piston into engagement with the groove walls of the adjustable sleeves.

8. In an engine of the class described, a shaft, a drum thereon, a pair of sleeves mounted on the drum, one end wall of each sleeve constituting one wall of a helical groove, tapered keys extending through openings in the sleeves and drum, means for adjusting said keys to compensate for wear on the groove walls, a reciprocatory piston, 50 and means extending from said piston into operative relation with the groove walls.

In testimony that I claim the foregoing as my own, I have hereto affixed my signature in the presence of two witnesses.

EMMETT H. HERNDON.
